ATTORNEY'S

UNITED STATES PATENT OFFICE.

HENRY A. OWEN AND OSCAR L. OWEN, OF WHITINSVILLE, MASSACHUSETTS,
ASSIGNORS TO THE WHITIN MACHINE WORKS, INCORPORATED, OF
WHITINSVILLE, MASSACHUSETTS.

SHIPPER-LOCK FOR DRAWING-FRAMES.

SPECIFICATION forming part of Letters Patent No. 737,863, dated September 1, 1903.

Application filed December 26, 1902. Serial No. 136,544. (No model.)

To all whom it may concern.

Be it known that we, HENRY A. OWEN and OSCAR L. OWEN, citizens of the United States, residing at Whitinsville, in the county of 5 Worcester and State of Massachusetts, have invented a new and useful Improvement in Shipper-Locks for Drawing-Frames, of which the following is a specification.

This invention has reference to improvements in automatic shipper-locks for drawing-frames, and more particularly to mechanism intermediate the shipper and the gear-covers of the drawing-frame operated by the opening or closing of the gear-covers to lock 15 or unlock the belt-shipper.

In drawing-frames the draft and change gears connected to the front roll-shaft are inclosed in pivoted covers secured in their closed position by spring-pins or other means. 20 These gear-covers may be opened by the operator to coil or change the gearing. As heretofore constructed there was great danger to the operator by the starting up of the machine from the belt-shipper being free to move 25 when the machine was stopped.

The object of this invention is to lock the belt-shipper when the machine is stopped with the belt on the loose pulley. The operator may now open the gear-covers to oil or change 30 the gearing without danger of the machine starting from an accidental movement of the belt-shipper.

To accomplish this object, our invention consists in the peculiar and novel construction of mechanism connecting the belt-shipper lock with the gear-covers, and by this mechanism the opening of the gear-covers locks the shipper and the closing of the covers unlocks the shipper, as will be more fully described hereinafter, and pointed out in the 35 claims.

Figure 1 is a side view of part of a drawing-frame, showing the fixed casing with the bearing for the locking-bolt, the front roll-shaft 45 with the fast and loose pulleys, and the shipper-bar with the locking-plate and shipper. Fig. 2 is an end view of Fig. 1, partly in section, showing the fixed casing supported on the frame, the locking-bolt and its connection with the top gear-cover pivoted to the

fixed casing, the front gear-cover pivoted to the frame, and the pivoted weighted arm connecting the front gear-cover with the locking-bolt, the belt and pulleys being shown in broken lines. Fig. 3 is an enlarged detail 55 view of the shipper-bar and shipper looking from the back, showing the locking-plate secured to the shipper-bar and the lower end of the locking-bolt.

In the drawings, *b* is the frame of the machine, supporting the fixed casing *b'*, with the bearing *b²* for the locking-bolt. The front roll-shaft *b³* is supported in bearings on the frame and carries the fast pulley *b⁴* and the loose pulley *b⁵*.

Pivotedly secured to the fixed casing *b'* is the top gear-cover *c*, with the cam *c'* in engagement with the upper end of the locking-bolt *e⁶*. The front gear-cover *d* is pivotally secured to the frame of the machine by the 70 bracket *d'* in engagement with the end *e³* of the arm *e'* and has the cam *d²*.

Secured to the under side of the frame *b* is the support *e*, forming a pivot for the arm *e'*, having the weight *e²* on the end *e³* and the 75 slotted end *e⁴* engaging with a pin *e⁵* on the locking-bolt *e⁶*. The shipper-bar *f* slides in the bearing *f'* on the frame *b* and has the shipper *f²* on its outer end in a position to control the belt on the fast and loose pulleys. 80

Secured to the shipper-bar *f* is the locking-plate *f³*, with the opening *f⁴* in a position to receive the lower end of the locking-bolt *e⁶* when the belt is thrown onto the loose pulley *b⁵* by the shipper.

In the operation of our improved shipper-lock the movement of either of the gear-covers to open or close controls the locking mechanism of the shipper-lock. When the operator wishes to gain access to the gears 90 inclosed by the gear-covers *c* and *d* to oil or change the gearing, he stops the machine by moving the shipper-bar *f* outward in the usual way. This throws the belt onto the loose pulley and brings the opening *f⁴* in the locking-plate *f³*, secured to the shipper-bar, in a 95 position under the lower end of the locking-bolt *e⁶*. The opening of the gear-cover *c* operates the cam *c'* to force the locking-bolt downward and into the opening *f⁴*, and the 100

opening of the gear-cover *d* operates the cam *d*² to raise the end *e*³ of the pivoted arm *e*' and lower the slotted end *e*⁴ in engagement with the locking-bolt, forcing the locking-bolt 5 downward and into the opening *f*⁴, locking the shipper, with the belt, on the loose pulley. When the gear-covers are closed, the weighted arm *e*' carries the locking-bolt upward, unlocking the belt-shipper. The machine may 10 now be started in the usual way.

Having thus described our invention, we claim as new and desire to secure by Letters Patent—

1. In a drawing-frame having gear-covers, 15 a shipper-bar and shipper, a locking-bolt, and locking mechanism connecting the gear-covers with the locking-bolt to lock the shipper when the gear-covers are opened, for the purpose as described.
2. In a drawing-frame having gear-covers, 20 a shipper-bar, a belt-shipper on the bar, a locking-bolt supported in a bearing on a fixed casing, a gear-cover pivoted to the fixed casing and having a cam in contact with the 25 upper end of the locking-bolt, and a locking-plate secured to the shipper-bar and having an opening to receive the lower end of the locking-bolt when the gear-cover is opened to lock the shipper, as described.
3. In a drawing-frame having gear-covers, 30 a shipper-bar and belt-shipper, a locking-bolt, means for supporting the locking-bolt, a locking-plate secured to the shipper-bar and having an opening to receive the locking-bolt, 35 a gear-cover pivotally secured to the frame

of the machine and having a cam, and a pivoted arm or lever secured near its center to the frame, one end engaging with the cam on the gear-cover and the other end engaging with the locking-bolt to lock the belt-shipper when 40 the gear-cover is opened, as described.

4. In a shipper-lock for drawing-frames, 45 the combination of the following mechanism: the gear-cover *c* having the cam *c*', the weighted arm *e*' pivotally supported on the frame, the locking-bolt *e*⁶ provided with the pin *e*⁵ engaging with the slotted end *e*⁴ of the arm *e*', and the shipper-bar *f* having the locking-plate *f*³ for locking the bolt *e*⁶ when the gear-cover is opened, as described. 50

5. In a shipper-lock for drawing-frames, 55 the combination of the following mechanism: the gear-covers *c* and *d*, each provided with cams and pivotally supported on the frame, the weighted arm *e*' pivotally supported near its center to the frame, the locking-bolt *e*⁶ provided with the pin *e*⁵ engaging with the slotted end *e*⁴ of the arm *e*', and the shipper-bar *f* having the locking-plate *f*³ for locking the bolt *e*⁶ when either one of the gear-casings 60 is opened, as described.

In testimony whereof we have signed our names to this specification in the presence of two subscribing witnesses.

HENRY A. OWEN.
OSCAR L. OWEN.
